CLAIM

The ornamental design for a jewelry item, as shown and described.

DESCRIPTION

FIG. 1 is a front perspective view of a jewelry item showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of a second embodiment of a jewelry item showing our new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines depicting gemstone settings and gemstones represent unclaimed portions of the jewelry item.

1 Claim, 6 Drawing Sheets
